UNITED STATES PATENT OFFICE.

JOHN J. ALVORD AND FRANK KARSITZ, OF BRIDGEPORT, CONNECTICUT.

DESIGN FOR A MEMBER OF A PAIR OF SHEARS.

42,385.

Specification for Design.

Patented Apr. 9, 1912.

Application filed September 20, 1911. Serial No. 650,473. Term of patent 14 years.

To all whom it may concern:

Be it known that we, JOHN J. ALVORD, a citizen of the United States, and FRANK KARSITZ, a subject of the King of Hungary, and both residents of Bridgeport, in the county of Fairfield and State of Connecticut, have invented a new, original, and ornamental Design for a Member of a Pair of Shears, of which the following is a specification, reference being had to the accompanying drawings, forming a part thereof.

In the drawings, Figure 1 is a plan view

of a shear member which illustrates our new design, and Fig. 2 shows an inside plan view of the same.

We claim:

The ornamental design for a member of a pair of shears, as shown.

JOHN J. ALVORD.
FRANK KARSITZ.
